Primary Examiner—Celia Murphy(74) *Attorney, Agent, or Firm*—Sheridan Ross P.C.(57) **CLAIM**

The ornamental design for a camera bag with accessories pouch, as shown and described.

DESCRIPTION

FIG. 1 is a perspective view of a camera bag with accessories pouch showing my new design. The broken lines showing gussets, interior dividers and pockets; straps, and handle throughout the views, illustrate the environment in which the design resides, and form no part of the claim.

FIG. 2 is a front elevation view of the invention illustrated in FIG. 1 shown in a closed position;

FIG. 3 is a rear elevation view of the invention illustrated in FIG. 2;

FIG. 4 is a right elevation view of the invention illustrated in FIG. 2;

FIG. 5 is a left elevation view of the invention illustrated in FIG. 2;

FIG. 6 is a top plan view of the invention illustrated in FIG. 2; and,

FIG. 7 is a bottom plan view of the invention illustrated in FIG. 2.
